UNITED STATES PATENT OFFICE

JOHN BOLDT, OF NEW YORK, N. Y.

WOODWORK-CHANNELING MACHINE

Application filed May 11, 1929. Serial No. 362,417.

This invention relates to new and useful improvements in woodwork channeling machines, and aims to provide a simple, compact and efficient machine that may be satisfactorily employed in home shops for use in the dove-tail channeling of woodwork, such as picture frames, window frames, door frames and the like.

An important object of this invention is to provide a machine of this character wherein the teeth of the cutters are radially adjustable and removable in order that the depth of the channel may be regulated, and in order that the cutters may be easily sharpened or renewed.

In the drawings wherein like reference characters indicate corresponding parts throughout the several views:

Figure 1 is a view partially in longitudinal cross section, and partially in side elevation of my improved machine.

Figure 2 is a detailed vertical section taken through the center of the machine substantially upon the line 2—2 of Figure 1, and looking towards one of the cutters, which is fragmentarily illustrated, and

Figure 3 is a fragmentary horizontal section through the cutter taken substantially upon the line 3—3 of Figure 2, for disclosing the position of the cutter teeth within the cutter unit.

Now having particular reference to the drawings, my novel machine consists of a suitable frame structure 5, preferably in the form of a casting. This frame is constructed to provide at opposite ends pairs of spaced shaft bearings 6—6 and 7—7, formed on an incline and within which are rotatably arranged respective shafts 6' and 7'. One of the shafts between its bearings is equipped with a belt pulley 8, in order that the machine may be power driven. However, if desired, said shaft may be equipped with a crank handle or other manually operable power means.

The inner ends of these shafts 6' and 7' are rounded out and are supported at their inner ends by a ball bearing 9, supported upon the upper end of a suitable standard 10 formed as a part of the frame casting 5 at the center thereof.

Arranged upon the extreme inner lower ends of these shafts 6' and 7' are intermeshing bevel gears 11 and 12, the back faces of which are formed with spaced radial channels 11' and 12', respectively. Loose upon each shaft in back of its particular gear is a collar 13 the inner face of each of which is also formed with spaced radially extending channels 14.

Adapted for arrangement between the adjacent faces of the respective gears and collars 13 are cutter teeth 15 formed at their opposite sides with longitudinally extending ribs 16—16 for arrangement within the channels of the gears and collars as more clearly illustrated in Figure 3. Directly in back of said collars 13, the respective shafts are screw threaded, and have threaded thereon tightening nuts 17 in order that the cutters will be tightly locked in adjusted position between the gears and collars.

From a consideration of Figure 1, it will be noted that the teeth of one shaft are arranged in staggered relation to the teeth of the other shaft so that they actually cross. At this crossing point, said teeth project through a slot in a suitable work support arranged upon the top of the frame 5.

In view of the foregoing description when considered in conjunction with the accompanying drawings, it will be apparent that I have provided a novel, simple and useful wood work channeling machine that is well adapted for all of the purposes heretofore designated, and even though I have herein shown and described the invention as consisting of certain detailed structural elements, it is nevertheless to be understood that some changes may be made therein, without affecting the spirit and scope of the appended claims.

Having thus described my invention, what I claim as new, and desire to secure by Letters Patent, is:

1. In a woodwork channeling machine, a frame, a pair of oppositely extending shafts journaled within the frame and inclining towards their inner ends, intermeshing bevelled gears upon the inner ends of the shafts, clamping collars loosely arranged upon the shafts in back of said gears, a plurality of

- radial cutting teeth arranged between the gears and collars of the respective shafts, the teeth of one shaft being arranged intermediate the teeth of the other shaft and said teeth crossing each other at a point in a vertical line bisecting the angle formed by the axes of said shafts, means associated with each shaft whereby to tightly maintain the collars in teeth securing position and a support for the inner ends of the shaft comprising a standard having a thrust ball mounted thereon, and embraced between the adjacent shaft ends.
2. In a woodwork channeling machine, a frame, a pair of oppositely extending shafts each having a recess in its inner end, said shafts being journaled within the frame and inclining towards their outer ends, a ball bearing support for the inner lower ends of said shafts, a thrust ball bearing mounted on said support and receiving the recessed ends of the shafts thereover, intermeshing gears upon the inner ends of the shafts and a plurality of spaced cutter teeth arranged upon the inner ends of the shafts.
